JOSEPH F. FRANTA, OF NEW YORK, N. Y., ASSIGNOR OF ONE-HALF OF HIS
RIGHT TO MICHAEL FARNAN, OF SAME PLACE; SAID FRANTA AND
FARNAN ASSIGNSORS OF ONE-THIRD OF THEIR RIGHT TO ERNEST MARX,
ALSO OF SAME PLACE.

DISTENDER FOR GAITERS.

SPECIFICATION forming part of Letters Patent No. 231,706, dated August 31, 1880.

Application filed January 28, 1880.

To all whom it may concern:

Be it known that I, JOSEPH F. FRANTA, of the city of New York, State of New York, have invented a new and useful Distender for Gaiters, of which the following is a specification.

My invention relates to a device to be used in the manufacture of gaiters for the purpose of facilitating the sewing by hand; and it consists, principally, in an elastic ring which is inserted into the uppers of gaiters and locked against compression, so as to distend the uppers and give ready access to the hand, and also expose the interior to view.

The annexed drawing is a perspective view of my distender for gaiters.

A is a ring, of brass or other elastic material, provided at one end with one or more slots, *a*, and at the other end with a tongue, *b*, which fits into the slots.

In using this instrument the same is compressed, inserted into the upper of a gaiter distended, and then locked against compression by passing the tongue into one of the slots *a*. The upper of a rubber gaiter is thus kept distended, and access to the inside for sewing, 25 for the hand, and the eye greatly facilitated.

Having thus described my invention, what I claim is—

The distending-ring for gaiters, provided with one or more slots at or near one end and 30 an outwardly-projecting tongue at the other end for locking the ring against compression, substantially as described.

JOSEPH F. FRANTA.
